CONTROL FOR HYDRAULIC COUPLINGS

James D. McCracken, Chicago, Ill., assignor to
Askania Regulator Company, Chicago, Ill., a
corporation of Illinois

Application August 31, 1942, Serial No. 456,806

3 Claims. (Cl. 60—54)

1

This invention relates to controls for hydraulic couplings, and, among other objects, aims to provide a cooling circuit for such couplings wherein the coupling fluid is circulated through the coupling in series with the coupling pump and a heat exchanger or cooler. One object of the invention is to control the circulation of the coupling fluid through the cooler to maintain a substantially uniform temperature. Another aim is to control the circulation through the cooler automatically in accordance with changes in the temperature of the fluid in the coupling. The series circuit of pipe communications for the coupling, cooler and pump include two valves automatically adjustable, one connected responsive to impulses from a master regulator and a bubbling device, and the other responsive to circulation temperature.

Other aims and advantages of the invention will appear in the specification, when considered in connection with the accompanying drawing, wherein the figure is a diagrammatic illustration of a control system embodying the invention.

The usual circuit for a hydraulic coupling control embodies a cooler connected in series with the coupling and oil is added to or taken away from the working circuit through a parallel circuit including the pump and the sump, and valves controlled by the master regulator which responds to a condition such as steam pressure in a boiler wherein the coupling is arranged between the motor and the fan which supplies combustion supporting air for the boiler furnace.

The coupling fluid, in the usual circuit, circulates at a rate which depends approximately on the load imposed upon the coupling. It is scooped out of the coupling and forced through a cooler ad back into the coupling. It leaks through ports into the scoop chamber at a rate which depends on the size and number of leak ports and on the mean depth of the oil in the working chamber. For any particular load, there is a definite rate of circulation which is not varied. As the temperature of the oil changes, the coupling efficiency varies. The present invention, therefore, provides means for maintaining the oil temperature substantially constant by controlling the rate of circulation of the oil through the series circuit.

Referring particularly to the drawing, the system is shown as being connected to operate a hydraulic coupling 5 which, incidentally, may be employed to rotate a fan (not shown) for supplying combustion air to a furnace, as shown in copending application Ser. No. 446,750, filed June 12, 1942, now Patent No. 2,392,300. The coupling

2

is connected in series with a cooler 6 and a pump 7 by means of pipes, as for instance pipe 8 having a valve 9 therein and pipe 10 with a vapor bulb 11 and valve 12. The series connection for the hydraulic fluid thus involves the coupling, the cooler and the pump.

The valve 9 is shown as being adjusted by means of a piston 13 movable in a cylinder 14 connected by pipes 15 and 16 to a well known jet pipe relay having a jet pipe 17 and a ratio slider 18. A pressure responsive diaphragm 19 is connected to a master regulator (not shown) by means of a pipe 20 and a second pressure responsive diaphragm 21 is connected by pipe 22 to a bubbling device 23. The two diaphragms 19 and 21 thus act on the jet pipe 17 and move the latter in response to pressures or to differential pressures on said diaphragms.

The bubbling device 23 receives its air under pressure from a supply pipe 24 and this device is submerged in an oil sump or container 25. A pipe 26 from the pump 7 acts to draw oil from the sump and pipe 27 permits oil to return to the sump after completing the circuit. A third pipe 28 having a relief valve 29 is adapted to act as a safety device in case valve 9 is not sufficiently open to take care of the oil forced from the pump 7.

The vapor bulb 11 transmits its expanded fluid to a flexible tube 30 by means of pipe 31, and this tube acts, by means of rod 32, on a jet pipe 33 counteracted by a spring 34 adjustable as to its force by means of the device 40. The hydraulic fluid from the jet pipe 33 enters both or one or the other of the pipes 35 and 36 to control a piston 37 in a cylinder 38. The piston 37 is connected to control or adjust the valve 12.

In the operation of the system, it will be understood that the pump 7 supplies oil continuously to the coupling 5 in response to a load. The jet pipe regulator 17 controls the valve 9 in response to changes in the load or the condition. The valve 12 remains partially opened and permits return flow of the oil picked up by the scoop tube 45 in the coupling through the pump circuit and the cooler. As the temperature of the oil varies, the vapor bulb 11 operates the regulator 33 to vary the position of the valve 12. The arrangement is such that, when the temperature increases, the valve will be opened wider to permit the return flow to increase. Lowering of the level in the coupling and the resulting rise in the level of the oil in the sump 25 will cause the regulator 17 to further open the valve 9. When the coupling load increases, which calls for an increase in

the supply of oil to the coupling, the regulator 17 will cause the valve 9 to open more until the level in the sump 25 is at a new reduced level which corresponds with the new load. Since the oil circulation is limited by the valve 12, the oil in the coupling will increase. The oil level and the valve 9 will cycle for a time or two and then find the equilibrium position. Decrease in the load will reverse the operation; that is to say, valve 9 will close more or throttle until the sump level increases to the new appropriate level and will then cycle once or twice until the valve 9 has found its equilibrium position again. If the valve 12 be opened to a greater extent to increase the circulation, the oil in the coupling will momentarily decrease. The level in the sump will increase and the coupling regulator will act to open the valve 9 and keep the sump level constant and permit a greater rate of circulation. It will therefore be understood that the valve 12 functions to control the circulation. Obviously, it may be employed to control the load and the valve 9 can control the circulation. Thus, the load control and the circulation control will both be fully automatic.

It is possible to place the valve 12 and bulb 11 and its associated elements in the pipe 8 between the pump 7 and the cooler 6, and the valve 9 together with its associated parts may be connected in the pipe 10 between the coupling 5 and pump 7.

Obviously, the present invention is not restricted to the particular embodiment thereof herein shown and described. Moreover, it is not indispensable that all the features of the invention be used conjointly, since they may be employed advantageously in various combinations and subcombinations.

What is claimed is:

1. In combination with a hydraulic coupling having a pipe circuit for supplying and returning the operating fluid, a pump and a cooler in said circuit connected in series with the coupling; a sump carrying the operating fluid into which excess returned fluid is delivered; a supply valve in the circuit between the pump and the cooler; an automatic regulator for said valve having an

air bubbling device connected to said sump to operate the regulator in response to variations of air pressure in the air bubbling pipe; and a temperature controlled valve in the fluid return portion of said circuit responsive to the temperature of the returning fluid to control the circulation of fluid through the cooler.

2. The combination set forth in claim 1, wherein impulse means responsive to a condition to be controlled is also connected to said regulator and acts in opposition to the impulses derived from air bubble device.

3. In combination with a hydraulic coupling having a pipe circuit for supplying and returning the operating fluid, a pump and a cooler in said circuit connected in series with the coupling; a sump carrying the operating fluid into which excess return fluid is delivered; a supply valve in the circuit between the pump and the cooler; an automatic regulator for said valve; impulse means, responsive to changes in the level of the fluid in said sump acting upon said regulator; opposing impulse means acting on said regulator in response to impulses derived from a condition to be controlled, whereby the supply valve may be operated to maintain a controlled condition substantially constant; a fluid return valve also arranged in the fluid circuit; and means responsive to the temperature of the returning fluid connected to operate said return valve.
